The ornamental design for a food container base, as shown and described.

DESCRIPTION

FIG. 1 is a top isometric view of a food container base showing another embodiment of our new design.

FIG. 2 is a bottom isometric view thereof.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof.

FIG. 8 is a right side elevational view thereof.

FIG. 9 is a cross sectional view taken from FIG. 3 in the direction of line 9-9;

FIG. 10 is a cross sectional view taken from FIG. 3 in the direction of line 10-10;

FIG. 11 is a top plan view of a food container base showing another embodiment of our design;

FIG. 12 is a bottom plan view thereof;

FIG. 13 is a front elevation view thereof;

FIG. 14 is a rear elevation view thereof;

FIG. 15 is a left side elevation view thereof;
FIG. 16 is a right side elevation view thereof;
FIG. 17 is a cross sectional view taken from line 17-17 on
FIG. 11;
FIG. 18 is a cross sectional view taken from line 18-18 on
FIG. 11;
FIG. 19 is a top plan view of a food container base showing
another embodiment of our design;
FIG. 20 is a bottom plan view thereof;
FIG. 21 is a front elevational view thereof;
FIG. 22 is a rear elevational view thereof;
FIG. 23 is a left side elevational view thereof;
FIG. 24 is a right side elevational view thereof;
FIG. 25 is a cross sectional view taken from line 25-25 on
FIG. 19; and,
FIG. 26 is a cross sectional view taken from line 26-26 on
FIG. 19.

Stippling in the drawings represent the three-dimensional
contours of the design, and are not intended to indicate
surface decoration. The broken lines in the drawings are for
the purpose of illustrating parts of the article that form no
part of the claimed design.
